UNITED STATES PATENT OFFICE.

JOSEPH N. PAUL FOURNIER, OF ST. HYACINTHE, QUEBEC, CANADA.

TOBACCO-PIPE.

1,133,015.

Specification of Letters Patent. Patented Mar. 23, 1915.

Application filed September 9, 1914. Serial No. 860,959.

To all whom it may concern:

Be it known that I, JOSEPH N. PAUL FOURNIER, subject of the King of Great Britain, residing at St. Hyacinthe, Quebec, Dominion of Canada, have invented certain new and useful Improvements in Tobacco-Pipes, of which the following is a description, reference being had to the accompanying drawing and to the figures of reference 10 marked thereon.

My invention relates to improvements in tobacco pipes, the object being to provide a tobacco pipe having a removable perforated diaphragm or floor for holding the tobacco 15 and ashes, and keeping them away from the bottom of the bowl, combined with a wick extending below the diaphragm into the space where the nicotin and liquid substances collect, and leading to the top of the 20 bowl to absorb such substances and prevent their passing into the smoke passage leading through the stem.

The invention includes various features, such as the perforated diaphragm or grate 25 above referred to, the absorbing wick, a movable grill with projections adapted to be brought into engagement with the perforations, to clear said perforations when they become clogged. The pipe may also have a 30 spoon-shaped plate upon which the lower end of the wick rests to keep the nicotin and liquid substances from touching the wood of the pipe and being absorbed thereby even to a slight extent.

35 The invention is illustrated in the accompanying drawings, in which—

Figure 1 is a side elevation with the bowl in section, of a pipe provided with my invention; Fig. 2 is a top plan view; Fig. 3 is a 40 vertical section through the bowl at right angles to the section of Fig. 1; Fig. 4 is a detached view of my improved attachment; Fig. 5 is a plan view of a portion of the diaphragm or grate with the supporting stem, 45 wick tube and moving grill operating rod shown in section; Fig. 6 is a view of a modification.

In these drawings, 1 represents the bowl of the pipe, which may be of any suitable 50 form and material. 2 is the stem and 3 the mouthpiece. The smoke passage is shown at 4.

My improved attachment comprises a vertical plate 5, adapted to be set into a recess 55 in the bowl. A small angle-wire or rod 6 is secured to the bowl and swings around

over the top of the vertical plate to hold the latter in position. The vertical plate 5 is formed hollow to receive a wick 7, which is threaded through it, and extends down to 60 near the bottom of the bowl below the smoke passage, so that it will absorb and suck up by capillary attraction the nicotin and liquid substances which would otherwise accumulate in the bottom of the bowl and be fed into 65 the smoke passage in the stem. Near the upper end, the wick tube has an opening 8, having a flap valve 9 over it. Through this opening the liquid substances on the wick may ooze out, but the valve is kept normally 70 closed by the suction of the smoker's inhalations, thus preventing a false draft through the wick tube. To the vertical plate 5 is attached a perforated diaphragm or grate 10, which extends across the bowl some 75 distance above the bottom, so as to leave a smoke space below it. This diaphragm or grate forms a support for the tobacco in the bowl. To clear the perforations, which are apt to become clogged, I form in the plate 80 5, or attach thereto, a guiding tube 11 to receive a rod 12 to the lower end of which is secured a plate 13 below the diaphragm 10. This plate 13 is normally pressed downwardly by a spring 14, and has projections 85 15 adapted when the rod 12 is raised (as shown in dotted lines in Fig. 4), to pass through the perforations and clear them. A single plate 16 may serve as the top of the vertical tube plate 5, and may be raised and 90 lowered to raise and lower the wick and the plate carrying the projections; or the rod 12 and the wick may be independently manipulated. To the lower end of the vertical plate 5 is also attached an oval or spoon-shaped plate 17, bent to conform to the curve 95 of the bottom of the bowl, and arranged below the stem smoke passage, so as to collect the nicotin and liquid substances. The lower end of the wick preferably rests on this 100 spoon, instead of on the bottom of the bowl. This spoon, however, may be omitted.

As a modification of the invention, I have shown in Fig. 6 an arrangement in which I dispense with the grate or diaphragm 10, 105 and form the spoon 17' with perforations and arrange the wick below it, although it might rest thereon.

It will be seen that I have provided an attachment for a pipe in the use of which a 110 perfect draft is afforded, clogging is prevented and greatest ease in cleaning results.

Having thus described my invention, what I claim as new and desire to secure by Letters Patent, is:—

1. In a pipe, the combination with the bowl, of a tube attached thereto extending to a point adjacent the bottom of the bowl, a tobacco supporting plate carried by said tube and adjacent the lower end thereof, and a wick extending through the tube adjacent the bottom of the bowl.
2. In a pipe, the combination with the bowl, of a perforated plate supported therein above the bottom of the bowl, a support for the same, a movable plate having projections engaging the perforations in said first plate to keep the same from clogging, and a wick tube carrying a wick extending into the bowl below the perforated plate.
3. In a pipe, the combination with the bowl, of a perforated plate supported therein above the bottom of the bowl, a support for the same, a movable plate having projections engaging the perforations in said first plate to keep the same from clogging, a wick tube carrying a wick extending into the bowl below the perforated plate, and a plate below the wick for catching the nicotin.
4. In a pipe, the combination with the bowl, of a perforated plate supported therein above the bottom of the bowl, a support for the same, a movable plate having projections engaging the perforations, in said first plate to keep the same from clogging, a wick tube carrying a wick extending into the bowl below the perforated plate, a plate below the wick for catching the nicotin, an opening in the wick tube, and a valve to cover the same to prevent a false draft.
5. An attachment for smoking pipes com-

prising a vertical plate supported by the bowl and having a horizontal perforated plate above the bottom of the bowl, to support the tobacco, a wick tube carried by said vertical plate and carrying a wick extending into the bowl below the level of the stem opening and leading to the exterior of the bowl.

6. An attachment for smoking pipes, comprising a vertical plate supported by the bowl and having a horizontal perforated plate above the bottom of the bowl to support the tobacco, a wick tube carried by said vertical plate and carrying a wick extending into the bowl below the level of the stem opening and leading to the exterior of the bowl, and a normally spring-retracted plate with points adapted to engage and clean the perforations.

7. An attachment for smoking pipes, comprising a vertical plate supported by the bowl and having a horizontal perforated plate above the bottom of the bowl to support the tobacco, a wick tube carried by said vertical plate and carrying a wick extending into the bowl below the level of the stem opening and leading to the exterior of the bowl, a normally spring-retracted plate with points adapted to engage and clean the perforations, and a curved plate or spoon for catching the nicotin and upon which the lower end of the wick rests.

In testimony whereof, I affix my signature, in the presence of two witnesses.

JOSEPH N. PAUL FOURNIER.
